UNITED STATES PATENT OFFICE.

HENRY ARMSTRONG, OF SYRACUSE, NEW YORK, ASSIGNOR, BY MESNE ASSIGNMENTS, TO MODERN ADVERTISING MACHINES LIMITED, OF OTTAWA, CANADA, A CORPORATION.

ADVERTISING MACHINE.

Application filed February 6, 1928, Serial No. 252,310, and in Canada February 10, 1927.

My present invention appertains generally to improvements in the art of advertising devices and specifically to a machine in which rollers carrying the advertising matter display curtains are transported back and forth across a predetermined display area, to successively exhibit and obliterate the advertising display matter.

The invention consists essentially of the novel features pointed out broadly and specifically in the claims for novelty following a description containing an explanation in detail of an acceptable form of the invention.

The principal objects of my invention are to provide a machine which will successively display a plurality of advertising matter display curtains to afford from the exhibition view point the same "growing in" and "wiping out" action as is provided by machines of the type referred to, and in which the rollers carrying the advertising display matter curtains are alternately and successively brought into display position so that all of the roller curtains are displayed in sequence, yet in which there is no indexing and interchanging of curtain rollers and in which the curtain rollers are at all times so retained that the possibility of accidental displacement is entirely obliterated; in which the display curtains may be highly illuminated without shadow; and wherein the minimum of "waste" display curtain material is required to support the display curtains for exhibition.

The machine comprises, in brief, a vertical frame or track, upon which a carriage is mounted for vertical reciprocation, or transverse reciprocation according to the adaptation, said carriage carrying in preferably two juxtaposed groups, the rollers carrying the advertising matter display curtains. The ends of the curtains remote from said rollers are connected to battens engaged with brackets employed to retain said curtain rollers in proper spaced relation. In operation, as said carriage is reciprocated, said groups of rollers are alternately adjusted to successively associate the rollers of said groups in pairs in a common roller curtain display area and the battens on the curtains supported by the curtain rollers adjusted to display position, are engaged with stationary hooks located at the ends of the display area, the latter serving to hold said curtains until the

battens thereof are released and re-engaged with said curtain roller retaining brackets.

In the present invention, detrimental characteristics of known machines are avoided by obviating curtain roller interchanging, and by indexing the battens on the free ends of the curtains at the extremities of the display area instead of indexing the curtain rollers. The indexing of the curtain battens is effected after the carriage carrying the curtain rollers has advanced to its farthest point of travel and has commenced to return, the indexing being brought about during the return travel of the roller carriage. Thus the roller carriage may travel beyond the point of curtain batten indexing without effecting the operation of the machine. This is a very important factor, since by such operation precision and incidental high cost of manufacture is avoided and frequent adjustment of the roller carriage driving means is unnecessary.

Other important advantages of the invention will become apparent ensuing a perusal of the following description read in conjunction with the annexed drawings, in which:

Fig. 1 is a front elevation of the machine as it would appear when taken on the plane of section of the latter being designated by line 1—1 on Fig. 2.

Fig. 2 is a vertical section of the machine, as it would appear when taken on the plane designated by the line 2—2 on Fig. 1.

Fig. 3 is a horizontal section as it would appear when taken on the plane designated by the line 3—3 on Figs. 1 and 2.

Fig. 4 is an enlarged section of the roller groups on the reciprocatable carriage, as it would appear when taken on the plane designated by line 4—4 on Fig. 1.

Fig. 5 is a fragmental front view of the section of the roller groups illustrated in Fig. 4.

Fig. 6 is an end elevation of the reciprocatable carriage on an enlarged scale, as it would appear when viewed in the direction indicated by arrow *a* in Fig. 1, and

Fig. 7 is a like view showing a relative position of the one roller group tripping or rotating mechanism.

Like characters of reference designate corresponding parts throughout the different views.

The term "display curtain" hereinafter

employed is intended to include all forms of flexible material and the matter contained thereon whether for pictorial display or advertising purposes; also the terms "reciprocatable" and "back and forth" as applied to travel of the display curtain roller supporting carriage are not intended to restrict the invention to the particular form disclosed.

In the present form of disclosure the case 10 of the machine is used to support certain components, in view of which the same is illustrated, the base thereof being designated by the numeral 6, the front by the numeral 7, and the back at 8, while the sides are indicated at 15 9 and 10 and the top at 11. The front of the machine is provided with a vision opening over which a sheet of glass 12 is mounted, and behind which a tapered frame or visor is located to add an aesthetic effect to the machine. The sides of the visor as indicated at 20 13, 14, 15 and 16, enclose or bound what is hereinafter designated as the curtain display area.

The frame of the machine generally indicated at 17 is provided with a base bracket 18 secured by screw 19 and to the case base 6 by screws 20 and 21. Brackets 22 and 23 connected to the top of the frame are fastened to the channel 24 extending across the top 11 30 of the case by means of bolts 25 and 26. Shims 27 and 28 are provided at the ends of said frame to facilitate proper location and for adjustment.

Channels 29 and 30 are formed in the said frame to receive journal ball bearings indicated by numerals 31 and 32, the two small bearings 31 being located in channel 29 and bearing against the edges thereof, while the larger bearings are disposed at right-angles 40 with respect to the smaller bearings and bear against the opposite sides of said frame channels. All said bearings are mounted on stub pins projecting from the carriage guide bracket 33, preferably in the form of a casting, through which the steel roller drive chain 34 passes, the latter being provided with a guide chair 35 which fits snugly within the lower end of said guide bracket, the contact faces of the guide bracket and guide chair being closely machined to assure proper alignment of the latter.

Two small rollers 36 and 37 are carried on the ends of pin 38 projecting through said guide chair 35 and drive chain 34. A transverse slot 39 is provided in the guide bracket 33 to receive roller 36 while the other side of the bracket is forked at 40 and 41 for the other roller 37, the object of the opening between the forks being to allow the lower end 60 of the guide bracket 33 to travel past the hubs of the drive sprocket 42 and idler sprocket 43. It will be observed in Fig. 3 that the guide chair 35 has projecting sides 44 and 45 so that the guide chair is not only retained in alignment within the guide bracket by means of

close contact therewith and rollers 36 and 37 described, but is also retained by straddling the sprockets referred to, when the bracket is being reversed in transit, as described later.

Idler sprocket 43 is mounted upon a journal ball bearing 46 supported by stub pin 47 extending into frame 17 referred to. Drive sprocket 42 is mounted upon the drive shaft 48 of a worm gear speed reducer generally indicated at 49, provided with a driving shaft 75 50 upon which drive pulley 51 is mounted, the latter being driven by the belt 52 trained thereover and over pulley 53 on the electric motor 54.

An automatic shut-off switch is provided 80 for the motor to stop travel of the guide bracket 33 and the reciprocatable carriage later described, when occasion demands, this being a most desirable feature as later more fully expounded. The drive pulley 51 is free 85 to rotate upon said shaft between fixed collars 55 and 56, the latter collar being cut away as at 57 providing a flat contact surface for the arm 58, which is pivoted to said pulley as at 59, and is held in contact by spring 60 on an adjustable pin 61 extending through pulley boss 62. A governor 63 is provided to lock arm 58 against the flat surface 57 on collar 56 to enable starting without operating the switch by the starting load. This governor 95 is pivoted between two bosses 64 and 65 and is tensioned downwardly by spring 66 on pivot pin 67 as indicated by arrow *b* in Fig. 2, so that the governor locking cam 68 contacts 100 with the upper edge of arm 58 and locks said arm in position. This locking feature counteracts the normal starting load and when pulley 51 picks up speed, governor 63 is forced outwardly radially by centrifugal force so that the cam 68 extends outwardly clear of the 105 arm 58. When an overload is imposed upon the driving chain 34, this is transmitted to shaft 50 of the speed reducer imposing a load thereon, so that the motor 54 will force arm 58 from the flat surface 57 on collar 56 to the 110 arcuate surface thereof, thus forcing said arm upwardly in direction of arrow *c*.

It will be observed from the location of pivot pin 59 that this action will throw the outer end of arm 58 outwardly beyond its concentric path of travel as denoted by circle *d* and will strike trip arm 69 pivoted on bracket 70 at 71. This trip arm serves to lock switch arm 72 pivoted to said bracket at 73, by means of pin 74 carried by arm 72 and extending into arcuate slot 75 in trip arm 69. A switch for breaking the light and motor circuit is provided and indicated at 76, the tumbler arm 77 thereof being located immediately above the end of switch arm 72. 125 When trip arm 69 is struck by the end of arm 58 as set forth, it is forced in the direction of arrow *e* and switch arm 72 is forced upwardly by spring 78, the pin 74 riding up slot 75, to limit the travel thereof and to pre- 130

vent damage to switch tumbler arm 77. By adjusting pin 61 any desired pressure may be exerted on arm 58 by spring 60. In view of the reduction in speed and leverage obtained by utilization of a worm gear speed reducer and the light operating load, little driving force is required to drive shaft 50 and consequently a very sensitive contact of pulley 51 with said drive shaft, and corresponding sensitive automatic switch, is provided.

Carriage guide bracket 33 is secured to a transverse carriage frame 79 having brackets 80 and 81 at the ends thereof. Journal ball bearings are retained in the retainers 82 mounted on the opposed faces of said brackets in pairs and corresponding spaced relation. Roller group shafts 83 and 84 extend through said journal ball bearings. Two brackets 85 and 86 are mounted in spaced relation on shaft 83. Shaft 84 is provided with two brackets indicated at 87 and 88, the latter two brackets being mounted in spaced relation with respect to the aforesaid brackets to provide working clearance.

Curtain rollers 89 and 90 are supported by said pairs of brackets in groups, the rollers of each said group being in equidistant spaced relation and at equal radial distances from a common axis of rotation. Each roller referred to is formed of a section of tube indicated at 91 mounted upon bearings contained in the ends thereof (not shown) which in turn are supported by the spindles 92 which extend longitudinally through said roller tubes and bearings and are supported by brackets 85, 86, 87 and 88. Springs 93 wound upon said spindles, are connected thereto and to the roller tubes. These springs serve to tension the curtain rollers for display curtain winding and unwinding purposes.

Display curtains 94 and 95 are connected in any suitable manner to the said curtain rollers 89 and 90 respectively and have battens 96 and 97 connected to the free ends thereof. These battens may be in the form of split tubes which grip the free ends of the display curtains. Pins 98 provided with tapered guide collars 99 extend from the ends of said battens. Brackets 85, 86, 87 and 88 have hooks 100 formed therein which engage the pins projecting from the ends of the said battens when the display curtains are wound upon the respective display curtain rollers and the battens are thus held in position under winding tension of the roller springs 93 until released for display, the tapered collars 99 on the end pins 98 serving to prevent end-wise shifting of said battens.

A curtain roller action concealing bar 101 is provided with brackets 102 and 103 which engage with the brackets 80 and 81 of the carriage frame, the relation of this bar with respect to the curtain rollers, display curtains thereupon, and the battens on the latter be-

ing such that it will just clear the same. This bar should be of sufficient width to hide from view, when viewed from the exhibition side of the display curtains, the roller winding action of the latter.

The two groups of curtain rollers referred to are alternately adjusted for sequential exhibition of display curtains by means of ratchet mechanism co-operating with stationary cam ratchet actuating means. Two ratchets 104 and 105 are mounted on shafts 83 and 84 respectively. Each ratchet is provided with four arcuately formed teeth 106 in equidistant spaced relation and the teeth of the two ratchets are opposed so that the directions of rotation will be reversed. Two ratchet dogs 107 and 108 are supported upon pins 109 and 110 carried by carriage frame bracket 80, and each said ratchet is provided with an end roller which engages the teeth of said ratchets, the same being tensioned thereagainst by springs 111 on pins 112 supported by lugs 113.

Two ratchet trip arms 114 and 115 are mounted upon journal ball bearings 116 and 117 on the ends of shafts 83 and 84 and carry ratchet dogs 119 and 120 pivoted on pins 121, said ratchet dogs being provided with rollers on the ends thereof which engage the teeth of said ratchets, the same being tensioned thereagainst by springs 122 supported by pins 123 protruding from lugs 124 and 125 on said trip arms. Pins 126 and 127 having journal ball bearings 128 and 129 mounted on the ends thereof, are carried by said trip arms 114 and 115, the two pins being in equidistant spaced relation with respect to the centres of shafts 83 and 84. A pin 130 extends from the centre of bracket 80 in the same vertical plane that shafts 83 and 84 are disposed in. A journal ball bearing 131 is mounted on the outer end of said pin in alignment with journal ball bearings 128 and 129.

The mechanism for tripping the ratchet trip arms includes a channel 132 having bracket plates 133 and 134 on the ends thereof, which are fastened to the brackets 135 and 136 on the side 9 of the case, by means of bolts 137 which also serve to support the trip cam brackets 138 and 139. The latter brackets are also supported by bolts 140 extending through lugs 141 and 142 on said trip cam brackets, and lugs 143 and 144 on bracket plates 133 and 134. Trip cams 145 and 146 channel-shaped in cross section, are provided on trip cam brackets 138 and 139. The arcuate contour of trip cams 145 and 146 is determined by the distance from the centres of shafts 83 and 84 to the centres of pins 126 and 127, such distance corresponding with the radii of said trip cams, as indicated at r . The length of the channel 132 and relation of the trip cams 145 and 146 is determined by the extent of travel of the reciprocatable carriage, as hereinafter more fully set forth.

- The two journal ball bearings 128 and 129 on ratchet trip arms 114 and 115 and the journal ball bearing pin 130 extend into the channel 132 and in proximity to the extremities of travel of the reciprocatable carriage the journal ball bearings 131 and 132 alternately enter and ride around trip cams 145 and 146 respectively, to trip the respective group of curtain rollers, as later defined.
- Journal ball bearing 131 on pin 130 operating in the stationary channel 132 supports the end of the reciprocatable carriage and prevents movement of the same with respect to the inner edges of the door visor 13, 14, 15, 16 referred to.
- To reduce the working load of the motor and stabilize travel of the reciprocatable carriage, which is visible through the bar 101, the reciprocatable carriage is counterbalanced by means of the counterweight 147 which runs on journal ball bearings 148 operating in channels 149 and 150 of frame 17 and journal ball bearings 151 which bear against the opposite sides of said frame. A steel roller chain 152, is connected at one end by means of screw 153 to said counterweight and is trained over idler sprocket 154, the other end thereof being connected to bracket 155 secured to the transverse carriage frame 79. Idler sprocket 154 is mounted on a journal ball bearing 156 supported upon pin 157 extending through the upper end of frame 17. Two hooks 158 and 159 are fastened by bolts 160 to brackets 135 and 136 on side 9 of the case and a pair of similar hooks 161 and 162 are secured by bolts 163 to brackets 164 and 165 on side 10 of the case. These hooks serve to retain the display curtain battens 96 and 97 when the display curtains are being exhibited. It is important that these hooks be so located with respect to the reciprocatable carriage that the brackets 85, 86, 87 and 88 which disengage the battens will lift the said battens clear of the said hooks. It is also essential that the centres of these hooks lie in the same vertical plane as the hooks 100 on said brackets, as clearly shown in Fig. 2 to enable proper engagement and disengagement of display curtain battens.
- It is very desirable to present, from an advertising viewpoint, a highly illuminated display curtain since this adds considerably to the attractiveness of the same. It is also necessary to obliterate all display curtain shadow and with this end in view illuminating electric lamps 166 are mounted on the brackets 167 on said transverse carriage frame 79. These lamps extend close to the display curtains in display position and intercept shadow which otherwise would be cast by the reciprocatable carriage travelling up and down in front of the illuminating electric lamps 168 supported by the conduits 169 and 170. The lighting circuit for the electric lamps 166 on the reciprocatable carriage includes two con-

tact rails 171 and 172 housed within the guard strips 173 and 174. Two metal brackets 175 and 176 extend from a porcelain or fibre cap 177 and carry contact brushes 178 and 179 which bear against the contact rails 171 and 172. The wiring leading from the brackets 175 and 176 to the lamps 166 may extend through the longitudinal opening 180 in the transverse carriage frame and through the brackets 167 to the electric light sockets which support the lamps 166.

In operation the reciprocatable carriage carrying the display curtain rollers 89 and 90 and the display curtains 94 and 95 carried thereby is reciprocated up and down in the machine case by means of the driving chain 34 and guide chair 35 within guide bracket 33, which guide chair rides over sprockets 42 and 43 reversing the direction of travel of said reciprocatable carriage. When the guide chair 35 on said driving chain is located centrally under driving sprocket 42 the centre of the reciprocatable carriage designated by line A—B lies in the plane indicated by the line E—F, and when said guide chair is located centrally over idler sprocket 43 the centre of the reciprocatable carriage as designated by line A—B lies in the plane depicted by line C—D. The lines C—D and E—F thus indicate the extent of travel of the reciprocatable carriage. The location of the trip cams 145 and 146 with respect to the extremities of the reciprocatable carriage travel is an important factor since these trip cams determine the accuracy of display curtain roller tripping and locking. It has been disclosed that the display curtain rollers 80 and 90 of the two roller groups are disposed in equidistant spaced relation at equal radial distances from a common axis of rotation and that the teeth 106 on the ratchets 104 and 105 are like formed. From this it is obvious that the ratchets must be tripped 90° by each tripping action to bring the curtain rollers into proper position for display since the latter are disposed 90° apart. However, to obviate precision and incidental high cost of manufacture and to facilitate assembling of the mechanism, the trip cams 145 and 146 are so located that the trip arms 114 and 115 are turned approximately $97\frac{1}{2}^\circ$, providing an over-ride on the ratchet teeth of $7\frac{1}{2}^\circ$, to ensure proper indexing of the ratchet dogs 107, 108, 118 and 119.

The foregoing is clearly depicted in Figs. 6 and 7 wherein the trip channel 132 and the upper trip cam 145 are indicated by dotted line. In Fig. 6 it will be observed that teeth 106 of ratchets 104 and 105 are bearing against end rollers on ratchet dogs 107 and 108, due to the tension exerted by the winding springs 93 in the curtain rollers in display position, which tension incidentally forces said ratchets in the direction indicated by arrows A and B. It will also be observed

that there is a clearance space C—D between the end rollers of the ratchet dogs 118 and 119 and the ratchet teeth 106, and that these ratchet dogs are in position for tripping.

5 When the reciprocatable carriage travels to one extremity of its plane of travel, for instance to line C—D, journal ball bearing 128 on pin 126 carried by trip arm 114 rides around trip cam 145 through the arc I—J—K 10 which is equivalent to $97\frac{1}{2}^\circ$, thus carrying the ratchet 104 so that the tooth 106 thereof in indexing position will ride $7\frac{1}{2}^\circ$ over the end roller on ratchet dog 107 leaving clearance space E in order that on return travel of 15 said reciprocatable carriage the trip arm 114 will ride back into alignment with the associated trip arm 115 and the ratchet 104 will move back $7\frac{1}{2}^\circ$ and tooth 106 thereof will again bear against the end roller of ratchet 20 dog 107. The action of trip arm 115, ratchet 105 and ratchet dogs 108 and 120 is similar. In this manner alternate adjustment of the display curtain rollers 89 and 90 is brought about and by virtue of the over-riding of the 25 ratchets 104 and 105 and the ratchet dogs 107 and 108, a positive, smooth operating, durable and practically noiseless trip action is provided.

Figs. 1 and 2 of the drawings show the reciprocatable carriage in substantially the centre of the display area, with two display curtains 94 and 95 in exhibition. Presuming that the reciprocatable carriage is travelling upwardly, after the bar 101 begins to disappear behind the upper edge 15 of the door visor, hooks 100 on brackets 85 and 86 pick up the batten 96 on the upper end of display curtain 94 and carry the same clear of the hooks 158 and 161, following which the upper 40 group of curtain rollers is adjusted by the ratchet trip mechanism described and the curtain roller 89 immediately above the curtain roller 89 formerly in display position behind the bar 101 is brought to such position and the 45 batten 96 on the display curtain 94 wound thereupon rides into the hooks 158 and 161 and is supported thereby so that this succeeding display curtain may be exhibited.

The reciprocatable carriage is then driven 50 downwardly and after the bar 101 passes the lower side 16 of the door visor hooks 100 on brackets 87 and 88 engage the batten 97 on display curtains 95 and lift the same clear of hooks 159 and 162, following which the lower 55 group of curtain rollers 90 is adjusted by the ratchet trip mechanism described and the curtain roller 90 below the curtain roller 90 carried from display position is adjusted to display position behind the bar 101 and bat- 60 ten 97 on display curtain 95 wound upon said curtain roller in display position is carried into hooks 159 and 162 which retain the same so that this display curtain is exhibited. In 65 this manner the reciprocatable carriage is transported back and forth behind the visor

and the several display curtains carried by the rollers of the respective curtain roller groups are brought into exhibition alternately and in sequence.

By providing for over-riding of the ratchets 104 and 105 and ratchet dogs 107 and 108 as described, and the indexing of the display curtain battens 96 and 97 on return travel of the reciprocatable carriage, positive operation of the machine is assured, providing the 70 same is mechanically constructed. In this respect attention is invited to the fact that sufficient clearance should be allowed in the design and mounting of the trip cam brackets 138 and 139 and the batten hooks 158, 159, 80 161 and 162 to accommodate for slight variation and distortion in the case construction.

The automatic electric current shut-off switch is a very desirable feature on the machine, since at times the curtain roller winding springs 93 break, and in such event it is necessary to immediately stop the machine before the display curtain and batten become entangled in the machine and cause destruction. By means of the mechanism described, 85 a very sensitive switch action is provided which will promptly shut off the motor (and lights if desired). This shut-off switch is also very useful when assembling the machine and on preliminary trial operations, 90 since the machine may be brought to a stop in the event that everything is not properly juxtaposed.

It will also be observed that the display curtains 94 and 95 are so supported by the 100 rollers 89 and 90 and battens 96 and 97 that there is very little waste material in the display curtains, which is an important cost factor when the display curtains are changed at frequent intervals.

While I have illustrated and described an acceptable adaptation of the invention it is obvious that the same is for the purpose of disclosure only, and that several modifications may be resorted to, to accord with commercial requirements, without departing from the gist of the invention and the scope of the annexed claims.

What I claim as new is:

1. In combination, display curtain rollers, 115 display curtains, said display curtains being connected to said display curtain rollers at one end only; battens on the other ends of said display curtains; means to support said display curtain rollers and said display curtain battens; means to transport said supporting means back and forth across a predetermined display area; stationary means to support said display curtain battens in proximity to the extremities of a predetermined display area; and means operating intermittently to bring said display curtain rollers into display position on said supporting means and to engage said display curtain battens with said stationary display curtain batten sup- 120 125 130

porting means, to exhibit said display curtains in sequence.

2. In combination, groups of display curtain rollers; display curtains, said display curtains being connected to the display curtain rollers of said groups of display curtain rollers at one end only; battens on the other ends of said display curtains; means to support said groups of display curtain rollers and said display curtain battens; means to reciprocate said supporting means across a predetermined display area; stationary means to support said display curtain battens in proximity to the extremities of travel of said groups of display curtain rollers and a predetermined display area; and means operating intermittently to alternately adjust said groups of display curtain rollers and bring the display curtain rollers of said groups of display curtain rollers into display position on said supporting means to engage said display curtain battens with said stationary display curtain batten supporting means, to exhibit said display curtains in sequence.

3. In combination, a frame, a carriage supported by said frame, means to reciprocate said carriage, display curtain rollers mounted upon said carriage, display curtains, said display curtains being connected to said display curtain rollers at one end only, battens on the other ends of said display curtains, means on said carriage to support said display curtain battens, stationary means to support said display curtain battens in proximity to the extremities of a predetermined display area, and means operating intermittently to bring said display curtain rollers in succession into display position on said carriage and to engage said display curtain battens with said stationary display curtain batten supporting means, to exhibit said display curtains in sequence.

4. In combination, a frame, a carriage supported by said frame, two parallel shafts journaled on said carriage, two brackets mounted on each said shaft in spaced relation, display curtain rollers disposed between and supported by said brackets, means to wind up and tension said rollers, display curtains on said rollers, battens connected to said display curtains, hooks on said brackets to engage and support said display curtain battens, means to reciprocate said carriage, means to alternately adjust said shafts to bring said display curtain rollers in succession into display position on said carriage, and stationary hooks to engage and hold said battens on said display curtains carried by the display curtain rollers in display position.

5. In combination, a frame, a carriage supported by said frame, two parallel shafts journaled on said carriage, two brackets mounted on each said shaft in spaced relation, display curtain rollers supported between

said brackets, means to wind up and tension said display curtain rollers, display curtains on said rollers, battens on the free ends of said display curtains, hooks on said brackets to engage and support said display curtain battens, means to reciprocate said carriage, means on said carriage co-operating with stationary means to alternately adjust said shafts to bring said display curtain rollers in succession into display position on said carriage, and stationary means to engage and hold said battens on said display curtains carried by the display curtain rollers in display position.

6. In an advertising machine, the combination with a machine case, of a reciprocatable carriage in said case; display curtain rollers carried by said carriage, display curtains on said rollers, stationary electric lights in said machine case to illuminate said display curtains during display curtain exhibition; and electric lights on said carriage to illuminate said display curtains during exhibition thereof and to prevent shadows being cast thereon.

7. In combination, a support arranged to travel back and forth through a definite range, a bracket rotatably carried by said support, a group of display curtain rollers mounted about the axis of said bracket, means controlling step by step rotation of said bracket to determine interchanged positions of said rollers, curtains, spring-wound upon said rollers having battens at their free ends, receiving means adjacent a limit of the range of travel of said support for receiving a portion of the batten of the curtain which is at the time in display position and holding it for the unwinding and winding of said curtain during the subsequent display period thereof, said bracket having receiving means for the battens of said curtains, one of which receiving means for each step of rotation of said bracket lies in a plane parallel to the direction of travel of said support and embracing said first-named receiving means, the range of travel of said support continuing sufficiently beyond said first-named receiving means to effect the transfer of a batten held by said first-named receiving means to said second named receiving means, and means also adjacent the limit of the range of travel of said support for imparting a rotational step of movement to said bracket, for moving the batten which has been transferred to said second named receiving means out of the common plane of both of said receiving means, and moving the batten of the curtain next to be displayed, into said common plane.

8. In combination, a support arranged to travel back and forth through a definite range, a bracket rotatably carried by said support, a group of display curtain rollers mounted about the axis of said bracket, means controlling the angular amplitude of steps of rotation assumed by said bracket to deter-

- mine interchanged positions of said rollers, and means adjacent a limit of the range of travel of said support constructed to impart step by step rotation to said bracket in steps of greater amplitude than that determined by said controlling means, whereby certainty in the positioning of said rollers is assured regardless of wide tolerances in the construction of the several elements of the combination. 5
9. In combination, a support arranged to travel back and forth through a definite range, a bracket rotatably carried by said support, a group of display curtain rollers mounted about the axis of said bracket, a rectilinear guide and means associated with said bracket engaging said guide, for holding said bracket nonrotatably during the display period of said range of travel, means adjacent the limit of said range of travel of said support for assuming control of said guide engaging means for moving the latter to impart a step of rotational movement to said bracket, and means controlling the angular amplitude 10 of the said step of rotational movement, to determine exact interchanged positions for said rollers prior to the re-assumption by said guide of the control of said bracket. 15
10. In combination, a support arranged to travel back and forth through a definite range, a bracket rotatably carried by said support, a group of display curtain rollers mounted about the axis of said bracket, a rectilinear guide and means associated with said bracket engaging said guide, for holding said bracket nonrotatably during the display period of said range of travel, means adjacent the limit of said range of travel of said support for assuming control of said guide engaging means for moving the latter to impart a step of rotational movement to said bracket, and means controlling the angular amplitude of the said step of rotational movement, to determine exact interchanged 20 positions for said rollers prior to the re-assumption by said guide of the control of said bracket, said means for imparting the steps of rotational movement to said bracket being constructed to impart said movement in steps of greater amplitude than that determined by the means controlling the angular amplitude of said movement, whereby certainty in the positioning of said rollers is assured prior to the re-assumption of the control of said bracket by said guide, regardless of wide tolerances in the construction of the parts of said combination. 25
11. In combination, rollers adapted to carry display curtains wound thereupon, a traveling support for said rollers, means for moving said support back and forth, means near an end of the range of travel of the rollers for holding the free ends of the curtains one at a time, cooperating with said support to unwind the held curtain, and means operating intermittently for bringing the rollers successively into position in which the curtains which may be wound thereupon will be successively engaged by said holding means. 30
12. In combination, groups of rollers, said rollers being adapted to carry display curtains wound thereupon, a traveling support for said groups, means for reciprocating said support back and forth, means near each end of the range of travel of said support for holding the free ends of the curtains one of each group respectively, at a time, said means being adapted to cooperate with said support to simultaneously unwind one of the held curtains and permit the other to wind, as said support reciprocates, and means operating intermittently to bring the rollers of the groups into position in which the curtains which may be wound thereupon will be engaged by said holding means, successively as to the rollers of a group, but alternately as to the groups. 35
13. In combination, groups of rollers, said rollers being adapted to carry display curtains wound thereupon, a traveling support for said groups, means for reciprocating said support back and forth over a display area, means near each end of the range of travel of said support for holding the free ends of the curtains one of each group respectively at a time, said means being adapted to cooperate with said support to simultaneously unwind one of the held curtains and wind the other as said support reciprocates, cooperating elements, carried, on the one hand, by said support, and on the other hand, being relatively fixed adjacent the respective holding means, for intermittently bringing the rollers of the respective groups successively into position in which curtains which may be wound upon said rollers may be engaged by the respective holding means. 40
14. In combination, groups of rollers, said rollers being adapted to carry display curtains wound thereupon, a traveling support for said groups, means for reciprocating said support back and forth over a display area, means near each end of the range of travel of said support for holding the free ends of the curtains one of each group respectively at a time, said means being adapted to cooperate with said support to simultaneously unwind one of the held curtains and wind the other as said support reciprocates, cooperating elements, carried on the one hand, by said support and on the other hand, being relatively fixed adjacent the respectively holding means, for intermittently bringing the rollers of the respective groups successively into position in which curtains which may be wound upon said rollers may be engaged by the respective holding means, and means adapted to maintain said held curtains in a plane path during the traverse of 45

the rollers of said held curtains across said display area.

15. In combination, two groups of rollers, each group being mounted on a rotatable bracket, said rollers being adapted to carry display curtains wound thereupon, a traveling support for said bracket, means for reciprocating said support back and forth over a display area, means near each end of the 10 range of travel of said support for holding the free ends of the curtains, one of each group respectively at a time, said means being adapted to cooperate with said support to simultaneously unwind one of the held 15 curtains and wind the other as said support reciprocates, and means operating intermittently to impart step by step rotation to said brackets for bringing the rollers of said groups into position to which the curtain 20 which may be wound thereupon will be engaged by said holding means successively as to the rollers of a group but alternately as to the groups.
16. In combination, a frame, a carriage supported by said frame, means to reciprocate said carriage, rollers adapted to support display curtains mounted on said carriage, means adjacent the limits of the range of reciprocation of said carriage for holding 25 the free ends of the curtains when said rollers have moved to a determined position, means to intermittently vary the relation of said rollers on said carriage to associate said rollers in sequence in pairs, and to bring them 30 into a common plane with said holding means.

17. In combination a frame, a carriage supported by said frame, means to reciprocate said carriage, through a range of movement including a determined display area, rollers adapted to support display curtains mounted on said carriage, means adjacent the limits of the range of reciprocation of said carriage for holding the free ends of the curtains when said rollers have moved to a determined 40 position, means to intermittently vary the relation of said rollers on said carriage to associate said rollers in sequence in pairs, and to bring them into a common plane with said holding means, and means for maintaining 45 the position of said rollers fixed with respect to the carriage while they are traversing said display area.

18. In combination, display curtain rollers, supporting means on which said rollers are 50 arranged in endless series, fixed means for engaging and holding the free ends of curtains of the spring-wound type with which said rollers may be provided, said supporting means being reciprocable so as to transport one of the rollers back and forth in a path which intersects and extends beyond said holding means, the free end of the curtain which may be carried by the said one roller being engaged and held by said holding 55 means to unwind the curtain in one di-

rection of travel of said supporting means and to permit the winding of the curtain and the lifting of the free ends thereof from said holding means upon the travel of said supporting means in the opposite direction, 70 means operative while the supporting means is in a position in which the free end of the curtain is lifted from said holding means to rotate the series of rollers through an angle at least sufficient to bring another roller successively into the position of the first mentioned roller, and means for holding said series of rollers in its newly assumed rotative position until the free ends of the curtain carried by said second mentioned roller are 80 brought into engagement with said holding means by the return movement of said supporting means.

19. In combination, display curtain rollers, supporting means on which said rollers are arranged in endless series, fixed means for engaging and holding the free ends of curtains of the spring-wound type with which said rollers may be provided, said supporting means being reciprocable so as to transport 90 one of the rollers back and forth in a path which includes a display area and which beyond said display area, intersects and extends beyond said holding means, the free end of the curtain which may be carried by 95 said one roller being engaged and held by said holding means to unwind the curtain in one direction of travel of said supporting means and to permit the winding of the curtain and the lifting of the free ends thereof from said holding means upon the travel of said supporting means in the opposite direction, means operative while the supporting means is in position in which the free end of the curtain is lifted from said holding means, to rotate the series of rollers through 100 an angle at least sufficient to bring another roller successively into the place of the first mentioned roller, and means for holding said series of rollers in its newly assumed rotative position until the free ends of the curtain which may be carried by the second mentioned roller is brought into engagement with said holding means, by return movement of 105 said supporting means, and means for positively maintaining said roller in its prescribed path throughout its extent of travel 110 over said display area.

20. In combination, a frame, a carriage supported by said frame, means to reciprocate said carriage, rollers adapted to carry display curtains, mounted upon said carriage, means operating intermittently serving to bring said rollers in succession into a position relative to said carriage in which 120 curtains carried by said rollers may be operated for the display thereof, by relative movement between said carriage and suitable means, the latter comprising stationary elements adapted successively to engage and 125 130

hold the free ends of the display curtains which may be carried upon said rollers.

21. In combination, a frame, a carriage supported by said frame, means to reciprocate said carriage, rollers adapted to carry display curtains, mounted upon said carriage, means operating intermittently serving to bring said rollers in succession into a position on said carriage in which curtains which may be wound thereupon may be displayed when suitably actuated, stationary means for engaging and supporting the free ends of the curtains which may be carried upon said rollers, and means mounted upon said carriage to conceal the winding action of the display curtain rollers from view, when viewed from a predetermined display area.

22. In combination, a carriage, means to support said carriage, means to reciprocate said carriage, two groups of display curtain rollers mounted upon said carriage, and means carried by said carriage cooperating with stationary means, to alternately adjust said groups of display curtain rollers, to bring the rollers of said groups successively into position on said carriage in which curtains wound thereupon may be displayed when suitably actuated, and means for engaging and holding the free ends of the said display curtains.

23. In combination, a carriage, means to support said carriage, means to reciprocate said carriage, two groups of display curtain rollers mounted upon said carriage, in parallel alignment, means carried by said carriage cooperating with stationary means to alternately adjust said groups of display curtain rollers to bring the rollers of said groups successively into position on said carriage, in which curtains wound thereupon may be displayed when suitably actuated, and means for engaging and holding the free ends of the said display curtains.

24. In combination, a carriage, means to support said carriage, means to reciprocate said carriage, two rotatable groups of display curtain rollers mounted in parallel relation on said carriage, means to partially rotate said groups of display curtain rollers when in proximity to the extremities of the reciprocating travel of said carriage to bring the display curtain rollers of said groups successively into position in which curtains wound thereupon may be displayed when suitably actuated, and means adjacent the said extremities of travel for receiving and holding the free ends of the curtains of the rollers that are, at the time, in the said display position.

25. In combination, a carriage, means to support said carriage, means to reciprocate said carriage, two groups of display curtain rollers mounted in parallel relation on said carriage, curtains spring wound upon said rollers, means operating intermittently serving to bring the display curtain rollers of

said groups in succession into position on said carriage to display two of the curtains when the latter are suitably actuated, and means for engaging and holding the free ends of the display curtains which at the time are in position to be displayed, to permit the curtains to be displayed, upon the alternate retreat of said carriage from said respective engaging and holding means.

26. In combination, a carriage, means to support said carriage, means to reciprocate said carriage, two groups of display curtain rollers mounted in parallel relation on said carriage, curtains spring wound upon said rollers, means operating intermittently serving to bring the display curtain rollers of said groups in succession into position on said carriage to display two of the curtains when the latter are suitably actuated, and means for engaging and holding the free ends of the display curtains which at the time are in position to be displayed, to permit the curtains to be displayed, upon the alternate retreat of said carriage from said respective engaging and holding means, and means to conceal the winding action of the display curtain rollers from view.

27. In combination, display curtain rollers, supporting means on which said rollers are mounted in two groups, the rollers of each group being arranged in endless series with one roller of each group being normally in position to display curtains which may normally be found thereupon, means for transporting said support with said rollers back and forth a predetermined distance, means adjacent the limits of said predetermined distance for engaging and holding the free ends of the curtains which may be wound upon the rollers that are in the said position to display said curtains, and intermittently operating means for alternately actuating said groups of rollers to bring the rollers of each group successively into curtain display position.

28. In combination, display curtain rollers, supporting means on which said rollers are mounted in two groups, the rollers of each group being arranged in endless series with one roller of each group being normally in position to display curtains which may normally be wound thereupon, means for transporting said support with said rollers back and forth a predetermined distance, means adjacent the limits of said predetermined distance for engaging and holding the free ends of the curtains which may be wound upon the rollers that are in the said position to display said curtains, intermittently operating means for alternately actuating said groups of rollers to bring the rollers of each group successively into curtain display position, and means for holding said rollers in this position during the period of transportation of said rollers across the area in which the curtains are displayed.

29. In combination, display curtain rollers, supporting means upon which said rollers are arranged in endless series, one roller at a time being normally in position to display a curtain which may be wound thereupon, means for transporting said rollers across a predetermined display area, means just beyond one end of said display area for engaging and holding the free end of the curtain carried by the roller which is in position at this time, to display said curtain, intermittently operating means for bringing said rollers successively into curtain display position, means for holding said rollers in their assumed position during their period of transportation across said display area, and means for holding said rollers in their assumed position immediately subsequent to their interchange of positions and in advance of their period of transportation across said display area.

30. In combination, a traveling support capable of back and forth movement, means for moving said support back and forth,

rollers for display curtains carried by said support, means permitting change in the relative positions of said rollers on said support, and means adjacent the limits of the range of travel of said support engaged by means moving with said support for changing the relative position of said rollers.

31. In combination, a traveling support capable of back and forth movement, means for moving said support back and forth, a bracket rotatably carried by said support, a group of display curtain rollers mounted about the axis of said bracket, interengagable elements respectively associated with said group of rollers and located adjacent the limits of the range of travel of said support for rotating said bracket to impart step by step rotational movement to said group, and means controlling the step by step rotation of said bracket to determine with exactness the interchanged positions of said rollers.

In testimony whereof I affix my signature.

HENRY ARMSTRONG.
